ROOF CONSTRUCTION

Thomas S. Bradley, San Leandro, Calif., assignor
to The Paraffine Companies, Inc., San Francisco,
Calif., a corporation of Delaware

Application June 24, 1929. Serial No. 373,319

10 Claims. (Cl. 108—5)

My invention relates to roofs, and particularly to metal railway car roofs.

One of the objects of the invention is the provision of a roof structure, which is characterized by economy and great durability.

Another object of the invention is the provision of a roof construction which is water-proof and rust-proof.

Another object of the invention is the provision of a roof of the character described, which is non-skid, thereby affording safety for persons walking on the roof in wet weather.

Another object is the provision of a roof construction which absorbs vibrations and prevents noise.

A further object of the invention is the provision of a roof of the character described which possesses improved wear-taking properties.

My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawing:

Figure 1 is a perspective view, partly in vertical section, of the railway car roof construction of my invention.

Figure 2 is an enlarged, fragmentary, vertical, sectional view of the top of the roof deck and the covering material which is united thereto, looking in the direction of arrow 2 of Figure 1.

In terms of broad inclusion, my invention comprises a railway car roof construction which is structurally a single unit, and which comprises an overlying layer of a fibrous sheet adhesively united to a sub-structure or deck. The fibrous sheet is saturated with a semi-solid material to render the sheet slightly and slowly yieldable under impact; and the sheet is preferably coated on its exposed surface with a water-proof material solid at normal temperatures.

With reference to the preferred embodiment of my invention in detail, the roof construction is illustrated in connection with a metal railway car 2 of any conventional construction and having the partially rounded metal deck 3. Overlying the deck 3, and disposed centrally and extending longitudinally thereof, is a layer 4 of a strip of fibrous material, such as a felt sheet manufactured by methods similar to that of roofing felt. It is preferred to use a felt which

in its untreated state weighs from 40 to 50 pounds per 480 square feet of material. It is obvious, however, that variations of this weight may be adopted, in accordance with the heaviness of material desired.

This sheet is treated by saturation with a bituminous material, such as the residue from California crude petroleum having a penetration of from 60 to 200 at 77° F., 100 grams, 5 seconds, according to the methods of the American Society for Testing Materials, Standards of 1927, and a softening point of 95° F. to 120° F., according to the same standards, and semi-solid at ordinary temperatures. The sheet is also preferably provided on the upper or exposed surface, or on both sides, with a coating 6 of bituminous material, such as asphalt solid at ordinary temperatures, and having a softening point of from 180° F. to 200° F. and a penetration of 12 to 20, according to the standards referred to in connection with the saturant. The coating 6 coalesces more or less with the saturant.

Before the coating has dried, the sheet is given a light dusting of a mineral powder 7, such as crushed creek or beach sand, the fineness being such that the material will pass thru an 80 mesh screen. It is apparent, however, that various other degrees of fineness may be employed, and that other similar material such as crushed rock, brick, or any other finely divided material may be used.

The fibrous strip is adhesively united to the metal deck 3 by a layer 8 of bituminous cement, preferably a relatively hard steam-blown asphalt dissolved in carbon disulfide, benzol or other suitable solvent. This cementing layer 8 forms a firm bond with the metal deck 3 and unites with the saturant or coating of the sheet, so that the deck and overlying layer 4 of fibrous material provide a unitary structure. This results in a structure having a rigid non-resilient base faced with a wear-taking layer firm under the impact of the feet of persons who may walk thereover, and possessing the peculiar property of "healing" over minor injuries in the surface, which may be caused by hob nail boots.

Heretofore, in order to protect metal railway car roofs against corrosion, particularly passenger car roofs, it has been customary to apply merely a coating of paint over the metal deck. It is apparent that after a short time the paint is chipped off at places by men walking over the roof, which occurs most generally on the central portion of the roof when the cars are being supplied with ice at division points, or when the cars

are being cleaned at terminals. Corrosion then sets in, and unless the roof is painted over at frequent intervals, the roof soon deteriorates. By the use of the described roof structure, the central part of the roof, subjected to practically all the wear, is protected by a wear-taking, water-proof and rust-proof covering, thus materially increasing the life of the roof. The side portions of the roof may be painted, according to usual practice, or, if so desired, the entire deck of the roof may be covered in the manner described.

Besides the advantages pointed out, the described roof construction is also a sound deadener; that is, it prevents noise and absorbs vibrations, so as to eliminate undue sound reverberations from entering the interior of the car. Another advantage of the construction is that the protective layer is non-skid, thus affording a measure of safety for workmen walking on the roof in wet weather, reducing the hazard of accidents under such conditions. Due to the latter, the described structure is especially applicable on freight car roofs, and can be used in place of the longitudinally extending runways usually provided on these cars.

Although the described construction is especially applicable in railway cars having metal decks, it is obvious that it may be employed with cars having non-metal decks.

I claim:

1. A railway car roof comprising a metal sub-structure, and an overlying wear-taking fibrous sheet treated with bituminous material, and adhesively united to the substructure.

2. A railway car roof comprising a metal sub-structure, an overlying fibrous sheet treated with bituminous material, and an intervening cementing layer of bituminous material to bind the whole into a unitary structure.

3. A railway car roof comprising a metal sub-structure, an overlying fibrous sheet, the fibrous sheet being saturated with a semi-solid material, and an intervening cementing layer of bituminous material to bind the hole into a unitary structure.

4. A railway car roof comprising a metal sub-structure, an overlying fibrous sheet saturated with a semi-solid bituminous material, and coated

on its exposed surface with bituminous material solid at normal temperatures, and an intervening cementing layer of bituminous material to bind the whole into a unitary structure.

5. A railway car roof comprising a substructure, and an overlying wear-taking fibrous sheet treated with bituminous material and adhesively united to the substructure. 80

6. A railway car roof comprising a substructure, an overlying fibrous sheet saturated and 85 coated with bituminous material, and an intervening cementing layer of bituminous material to bind the whole into a unitary structure.

7. A railway car roof comprising a metal sub-structure, and an overlying wear-taking fibrous 90 strip extending longitudinally of the car roof, said strip being treated with bituminous material, and adhesively united to the substructure.

8. A railway car roof comprising a substructure, and an overlying wear-taking fibrous strip 95 extending longitudinally of the car roof and saturated with a semi-solid bituminous material, and coated on its exposed surface with bituminous material solid at normal temperatures, and an intervening cementing layer of bituminous mate- 100 rial to bind the strip to the substructure.

9. A railway car comprising a roof, a centrally disposed strip of fibrous material extending longitudinally of the roof and adhesively united therewith, said strip being of a width less than 105 the width of the car and being saturated with semi-solid bituminous material and coated on its exposed surface with semi-solid bituminous material solid at normal temperatures and providing a non-skid waterproof wear-taking runway 110 for protecting the roof.

10. A railway car comprising a roof, a centrally disposed strip of fibrous material extending longitudinally of the roof, said strip being of a width less than the width of the car and 115 being saturated with semi-solid bituminous material and coated on its exposed surface with semi-solid bituminous material solid at normal temperatures and providing a non-skid waterproof wear-taking runway for protecting the 120 roof, and a layer of bituminous cementing material between the roof and the strip to bond the whole into a unitary structure.
